UNITED STATES PATENT OFFICE.

EDITH M. CRAFT, OF CLEVELAND, OHIO.

COMBINED CURTAIN STRETCHER AND CLOTHES RACK.

Application filed December 21, 1925. Serial No. 76,826.

My invention is a combined curtain stretcher and clothes rack, and it consists of the combinations, constructions and arrangements herein described and claimed.

5 An object of the invention is the provision of a device of the character described which affords facilities for supporting a plurality of curtains of any one of a plurality of different sizes without the use of the usual fastening pins for engaging with the curtain and so that the entire areas of both faces of each curtain will be unobstructed and exposed to the air.

10 A further object of the invention is the provision of a device of the character described which affords facilities for supporting garments in the manner of a clothes rack or costumer.

15 A still further object of the invention is the provision of a device of the character described which can be folded to take up but relatively little space and which can be quickly and easily adjusted for use either as a curtain stretcher or a clothes rack or for 20 use as both a curtain stretcher and a clothes rack.

25 Other objects and advantages of the invention will be apparent from the following description, considered in conjunction with 30 the accompanying drawings, in which—

Figure 1 is a perspective view of the device as it appears in use as a curtain stretcher.

35 Figure 2 is a fragmentary perspective view of a portion of the device used to support articles of wearing apparel.

40 Figure 3 is a fragmentary vertical section through one of the standards of the device and through a bracket on the standard, 45 showing means for releasably holding the bracket against vertical movement on the standard.

Figure 4 is a fragmentary view, partly in 50 side elevation and partly in vertical section, 55 showing the upper end portion of one of the standards and a bracket on the upper end of said standard.

55 In carrying out the invention, I provide a pair of standards 1 which may be made 60 of wood, metal or any other suitable material and which may be tubular, as shown, or solid, if desired. Each standard 1 has a base 2 which is of suitable size and shape 65 to firmly support the standard in an upright position on a floor 3 or other horizontal surface, the base preferably having a

flat lower face adapted to rest flatwise on the supporting horizontal surface and the standard preferably extending upwardly from the center of the base. 60

Each standard 1 is formed with two vertical rows of spaced transverse openings 4 and 5, respectively, the openings 4 lying in a vertical plane which extends substantially at right angles to the vertical plane in which the openings 5 lie. 65

An upper bracket 6 and a lower bracket 7 are associated with each standard 1. The upper bracket 7 comprises a member of bar-like form enlarged vertically intermediate 70 its length as indicated at 8, this vertically enlarged middle portion of the upper bracket being formed with a vertical socket 9 in its lower face for the reception of the extreme upper end portion of the associated 75 standard 1. The middle portion of this upper bracket 6 therefore may be termed a cap. A pair of oppositely extending or aligned lateral supporting arms 10 extend from the cap portion 8 of each upper bracket 80 6 and have the extreme end portions thereof reduced and turned upwardly and inwardly to produce the hooks indicated at 11. Each supporting arm 10 of the upper bracket 6 is formed with a plurality of 85 spaced transverse openings 12 which preferably are non-circular in cross sectional configuration as best seen in Figure 4. Each lower bracket 7 is made of a bar-like member which is enlarged laterally at opposite 90 sides intermediate its length as indicated at 13, this laterally enlarged middle portion of the lower bracket being formed with a vertical bore or opening 14 for the reception of the associated standard 1 so that the lower 95 bracket 7 may slide and rotate on the associated standard. Each lower bracket 7 also includes a pair of oppositely extending or aligned lateral arms 15 similar to the arms 10, the extreme outer end portion of each 100 of the arms 15 being reduced and turned upwardly and then inwardly to produce a hook, such as shown at 16. Each arm 15 is formed with spaced transverse openings 17 105 similar to the openings 12 in the arm of the upper bracket 6, the openings 17 being preferably non-circular in cross section and corresponding in number and relative arrangement with the openings 12 in the corresponding arms of the upper bracket 6 on the same standard. A pin 18 which is adapted 110 to be inserted in any one of the openings 4

115

or 5 of the associated standard 1 and to protrude from such opening is attached by a chain 19 to an arm 15 of the lower bracket 7, there being a pin 18 and a chain 19 for each arm 15 of each lower bracket.

A plurality of pairs of upper and lower cross rods, such as indicated at 20 and 21, respectively, are provided for each pair of standards 1 and the brackets on said standards. The end portions of each upper cross rod 20 are formed to fit in corresponding or aligned openings 12 of corresponding arms 10 of the upper brackets. The end portions of each cross rod 21 likewise are adapted to fit in corresponding openings 17 of corresponding arms 15 of the lower brackets. Each upper cross rod 20 is extended through the usual hem 22 at the upper end of a curtain 23 which is to be stretched and dried and the corresponding lower cross rod 21 is extended through the hem 24 at the lower end of that curtain. The lower brackets 7 then are adjusted on the standards 1 until the curtain is stretched as desired and these lower brackets then may be secured against accidental movement on the standards 1 by means of the pins 18, one of the pins 18 which are associated with each lower bracket 7 being inserted in one of the openings 4 just above the middle portion of the associated bracket 7 while the other pin 18 that is associated with that lower bracket being inserted in an opening 4 just below the middle portion of the associated bracket 7.

It will be obvious that a plurality of curtains may be supported by the device and that the entire areas of both faces of the curtains will be exposed to the air. When the device is used as a curtain stretcher and drier, as shown in Figure 1, articles of wearing apparel may be hung on the outer end portions of the bracket arms. However,

when it is desired to use the device as a clothes rack only, the lower bracket 7 on each standard 1 preferably is raised on that standard nearly to the upper bracket and then is arranged substantially at right angles to the upper bracket and is secured against accidental displacement from the desired position on the associated standard by means of the pins 18, which are inserted in suitable openings 5.

Obviously, my invention is susceptible of embodiment in forms other than that illustrated in the accompanying drawing and I therefore consider as my own all such modifications and adaptations of the form of the device herein described as fairly fall within the scope of the appended claim.

I claim:—

A device of the character described comprising a pair of standards, each having a vertical series of spaced transverse openings, a bracket having a socket in the underside of the middle portion thereof fitting on the upper end of a standard, there being one of said brackets for each standard, each of said brackets also comprising a pair of oppositely extending lateral arms, a second bracket for each standard, said second named bracket having a vertical opening in the middle portion thereof for the reception of said standard and being slidable on said standard, said second named bracket also including a pair of oppositely extending lateral arms, the arms of all of said brackets having similar transverse openings for the reception of end portions of cross rods, and pins removably engageable with transverse openings of the associated standard to prevent vertical movement of the second named bracket on that standard.

EDITH M. CRAFT.
